United States Patent Office

Des. 184,503
Patented Mar. 3, 1959

184,503

TRIVET OR SIMILAR ARTICLE

Emil Otto Bauerle, Chicago, Ill.

Application September 9, 1958, Serial No. 52,576

Term of patent 14 years

(Cl. D44—10)

I claim:

The ornamental design for a trivet or similar article, substantially as shown.
